UNITED STATES PATENT OFFICE

PATRICK J. FITZGERALD, OF TORRINGTON, CONNECTICUT, ASSIGNOR TO THE FITZGERALD MANUFACTURING COMPANY, OF TORRINGTON, CONNECTICUT, A CORPORATION OF CONNECTICUT

SEPARABLE BEATER FOR MIXING DEVICES

Application filed April 19, 1932. Serial No. 606,205.

This invention relates to a form of construction of a separable beater which may be employed with mixing devices of the type disclosed in my co-pending application Serial 5 No. 543,921, filed June 12, 1931.

One feature of the present invention is the provision of a separable beater which may be constructed of few parts and in simple manner, and which is rigid during service.

10 Another feature of the present invention is the provision of a separable beater having paddle members with projections for engaging with flat portions of a driving and supporting spindle whereby the paddles are 15 locked to the spindle for rotation.

A further feature of the present invention is the provision of a separable beater including a driving spindle which is deformed to provide driving projections for 20 establishing operative relationship with a slotted driving sleeve on the mixing device.

With these and other objects in view as will appear in the course of the following specification and claims, an illustrative form 25 of practicing the invention is set forth on the accompanying drawing, in which:

Figure 1 is a diametrical section along the axis of a beater according to the present invention.

30 Fig. 2 is a similar view at right angles to that of Fig. 1, and showing the parts prior to the assembly of the spindle therewith.

Fig. 3 is a detail sectional view substantially on line 3-3 of Fig. 1.

35 Fig. 4 is a detail sectional view, on a larger scale, substantially on line 4-4 of Fig. 1.

Fig. 5 is a similar detail sectional view, substantially on line 5-5 of Fig. 1.

Fig. 6 is a diagrammatic view, showing 40 the manner of forming the driving projections.

In the drawing, a spindle 60 is provided with a retaining groove 62 intermediate its length, the driving projections 61 which are 45 preferably located below the retaining groove 62, and with the flattened portions 64 adjacent the lower end for establishing a driving relationship with the paddles, as will be described hereinafter: each of these flattened portions is preferably formed by cutting two

55 pairs of parallel diagonal grooves in the spindle, each groove being of V-shape, and the four grooves at their bottoms extend chordally and leave a rectangular section of the spindle (Fig. 4).

The beater portion proper comprises paddles which are preferably formed of sheet metal strips of arcuate section for rigidity, by bending a strip into U-shape and approximating the ends while holding them substantially parallel and at a distance apart corresponding to the diameter of the spindle 60 (Fig. 2). Either prior to or after this approximation, the strips are provided with inward projections 15, preferably by depressing the material (Fig. 1) adjacent the ends thereof. The two strips thus formed are shown as non-identical as one passes above the other at the bottom of the beater. The formed paddle strip 10 (Fig. 1) passes beneath the formed paddle strip 11. The two paddle strips are joined together by forming an eyelet 14 or tubular portion along the axis of the device, directed toward, and adapted to be passed through a corresponding aperture formed in the other paddle strip 11. It is preferred, as illustrated, to form this eyelet or tube in the lower strip, so that upon clinching the inner end of the eyelet into position as shown in Fig. 3, to hold the two strips together, the irregularities of the device are on the inside, and thereby a smooth bottom is provided for the beater as a whole. The eyelet is inserted through the opening of 70 the other strip and then clinched as shown in Fig. 3, thus yielding a partial assembly 75 of the type shown in Fig. 2, where the four upper ends of the strips are brought together and as a whole provide a split sleeve having 80 substantially the same internal diameter as the external diameter of the spindle 60: that is, each of the strips has at its end an arcuate section conforming to the spindle 60 and extending through an arc of 90 degrees.

85 The spindle 60 may be manufactured by cutting rod material to the appropriate length and forming the holding groove 62 annularly therein, and cutting the driving flat portions 64. Either prior to or subsequent to such operations, the spindle is pro- 100

vided at a predetermined distance from its ends with the driving projections 61. It is preferred to provide these driving projections 61 by squashing the spindle transversely in the manner indicated in Fig. 6, in which the spindle blank 60a is placed upon a matrix M having a groove 20 of cylindrical conformation to receive the body of the spindle at points axially removed from the projection 61 and provided at the locations for the projection 61 with inwardly extending forming portions 21. A die D is employed in conjunction therewith, having a groove 22 corresponding to the groove 60 and the forming portions 23 corresponding to the opposite forming portions 21. As the die is brought down upon the rod, it causes a crushing and lateral forcing of the metal from the simple cylindrical shape into the X-shape shown in Figs. 5 and 6, with the projection 61 extending beyond the general cylindrical surface of the spindle 60.

Such a spindle is then slipped into the partial assembly of Fig. 2 until the projections 15 fit into the groove 64 (Figs. 1 and 4) and then a ferrule 30 is forced along the spindle 60 and over the upper ends of the paddle strips: a tight driving fit is thus accomplished, whereby a rigid assembly is produced between the spindle and the paddle strips.

In use, the separable beater operates with the structure shown in my co-pending application Ser. No. 543,921 above referred to, as the spindle 60 slips into the driving sleeve 39 and is held against downward dropping by the engagement of the ball 49 in the groove 62, this ball itself being held in position by the clutch cone 46. When in this

position, the driving projections 61 occupy notches 41 formed in the lower end of the driving sleeve 39.

It is obvious that the invention is not limited solely to the form shown, but that it may be modified in many ways within the scope of the appended claims.

Having thus described the invention, what I claim as new and desire to secure by Letters Patent, is:

1. A separable beater for a mixing device comprising a driving spindle having chordally extending grooves adjacent one end of the spindle and arranged to form said spindle polygonal in cross section, two paddle strips providing paddles and having their ends provided with offset portions engaging in said grooves, and a ferrule for holding said projections in said grooves.

2. A separable beater for a mixing device comprising a cylindrical driving spindle cut away adjacent one end at diametrically opposite points to provide angular surfaces about the spindle, a beater paddle formed of a strip of sheet metal and having its center extending at right angles to the axis of the spindle and having its ends brought together into substantial parallelism, said substantial parallel end portions of the paddle being arcuate transversely to conform with the curvature of the spindle and engaging said spindle and overlapping said cut-away portions, inwardly extending portions on said strip of metal extending into said cut-away portions, and a ferrule tightly fitting around the ends of said strip to prevent radial separation thereof from the spindle.
